UNITED STATES PATENT OFFICE.

WILLIAM HENRY MORGAN AND WALTER V. HARTZELL, OF ALLIANCE, OHIO; SAID HARTZELL ASSIGNOR TO SAID MORGAN.

METAL TIES FOR RAILROADS.

1,026,106.

Specification of Letters Patent.

Patented May 14, 1912.

Application filed May 15, 1911. Serial No. 627,270.

To all whom it may concern:

Be it known that we, WILLIAM H. MORGAN and WALTER V. HARTZELL, citizens of the United States, and residents of Alliance, 5 in the county of Stark and State of Ohio, have invented certain new and useful Improvements in Metal Ties for Railroads; and we do hereby declare the following to be a full, clear, and exact description of the 10 invention, such as will enable others skilled in the art to which it appertains to make and use the same.

Our invention relates to an improvement in metal ties for railroads, and is designed 15 particularly as an improvement on the construction disclosed in application No. 615,423 filed March 18th, 1911, by William Henry Morgan.

The ties shown in the above application 20 are all Z-shape in plan with parallel members running in the direction of the length of the rails for supporting the latter, each rail supporting member being bent outwardly at its end to prevent lateral tilting of 25 the ties.

The object of this invention is to cheapen 30 the cost of production of the ties, and also to provide simple and efficient means for maintaining the gage of the track and absolutely preventing any spreading due to the elasticity or flexibility of the Z-shape ties.

A further object is to provide means for anchoring the track to the road bed, so as to prevent longitudinal creeping of the track 35 on grades, the parallel rail supporting members of the Z-shaped ties, preventing all lateral creeping.

With these and other objects in view our 40 invention consists in a series of Z-shaped metal ties, and straight metal ties alternating with the Z-shaped ties and projecting at the sides beyond the rail supporting members of the latter.

Our invention further consists in means 45 for clamping the straight ties to the rails.

Our invention further consists in the details of construction and combinations of parts as will be more fully explained and pointed out in the claims.

50 In the accompanying drawings, Figure 1 is a view in plan of a section of track embodying our invention. Fig. 2 is a view in side elevation of one of the straight ties showing the rails secured thereon. Fig. 3 is 55 a view in section on the line α — α of Fig. 1.

Figs. 4, 5 and 5^a are views in perspective showing the means for securing the rail holding means to the tie. Fig. 6 is a view of the blank from which the rail securing plates are made, and Fig. 7 is a plan view showing the Z-shaped ties with outwardly bent ends and straight ties intermediate the Z-shaped ties.

1 represents a series of Z-shaped ties, each comprising parallel rail supporting members 2, and a body 3 portion connecting the rail supporting members, all of said parts being integral, and 4 are the straight ties arranged alternately between the Z-shaped ties, and projecting as shown beyond the rail supporting members of the latter. Both the straight and the Z-shaped ties are I-shaped in cross section, with the base flanges 5 wider than the top flanges 6, the base flanges of the Z-shaped ties being cut away or of reduced width at the bends, so as to facilitate the bending. These ties are preferably made from old rails as shown in Fig. 3, the base flange of the rail section forming the top flange 6 of the tie, and the head 7 of the rail, shown in dotted lines in Fig. 3, being flattened out to form the wider base flange, as explained in the application above referred to, but they can of course be made direct from new material.

In order to prevent longitudinal creeping of the track, we flatten out the base flange at the center of the straight ties as shown at 8 in Figs. 1 and 3, and thus provide elongated anchors extending longitudinally of 90 the tie, and of depth sufficient below the tie, to anchor the latter against the possibility of creeping in the direction of the length of the track, lateral creeping being prevented by the rail supporting sections of the Z- 95 shaped ties, which are embedded in the ballast.

9 are the straight tie rail securing plates to which the track rails are secured. These plates are made from rectangular blanks, 100 shown in Fig. 6 and slotted at each end as at 9^a. The four tongues 11 formed by slitting the plate 9, are bent downwardly and under the top flanges of the tie as shown in Figs. 4 and 5, the central tongues projecting at 105 the two sides of the tie for the attachment of the rail securing clamps 13.

The tie 4 is provided with lugs 14, formed by displacing the metal from below, which lugs form abutments for the opposite sides 110

of the plates 9, and hold the latter against sliding movement on the ties, while the bent lips 11 hold the plates 9 down on the ties. The plates in turn are provided with upwardly projecting shoulders 15, formed by displacing the metal from below, which shoulders form side abutments for the rail, and operate to hold the latter in proper position on the plates, and the horizontal tongues 12 of said plates are provided with depending ribs 16, formed by displacing the metal from above, for the attachment of the spring clamps which latter form the subject matter of our application Serial 15 Number 615,397 filed March 18, 1911. By this construction we are enabled to use the same clamps for securing the rails to the straight ties, as are used on the ties having parallel members running in the direction 20 of the length of the rails and on which the rails are supported.

If desired we may use the Z-shaped ties having parallel rails supporting members with outwardly bent ends, as shown in Fig. 25 7, thus increasing materially the bearing surface of the ties at points outside of the rails, and if desired we may also dispense with the anchors depending from the straight ties, and depend on the contact of the latter with 30 the ballast, to prevent endwise creeping of the track.

It is evident that many slight changes might be resorted to in the relative arrangement of the parts shown and described with 35 out departing from the spirit and scope of our invention. Hence we would have it understood that we do not wish to confine ourselves to the exact construction and arrangement of parts shown and described, 40 but

Having fully described our invention what we claim as new and desire to secure by Letters-Patent, is: -

1. The combination of a series of metal 45 ties, the ends of each of which are bent into

parallel planes to form carrying members for the rails, and straight ties alternating with the bent ties, the ends of the straight ties projecting beyond the carrying members of said bent ties.

2. The combination of a series of metal ties the ends of each of which are bent into parallel planes to form carrying members for the rails, the said carrying members having outwardly bent ends, and straight ties alternating with the bent ties, the ends of the straight ties projecting beyond the carrying members of said bent ties. 50

3. The combination of a series of Z-shaped metal ties, the parallel ends of which 60 form the rail supports, and straight ties alternating with the Z-shaped ties.

4. The combination of a series of Z-shaped metal ties the parallel ends of which form the rail supports, and straight ties 65 alternating with the Z-shaped ties and projecting at the sides of the rails beyond said Z-shaped ties.

5. The combination of a series of Z-shaped metal ties, and straight ties alternating with the Z-shaped ties, the straight ties having depending anchors extending lengthwise the tie. 70

6. The combination of a series of Z-shaped ties having parallel ends extending 75 lengthwise the rails for supporting the latter, and straight ties alternating with the Z-shaped ties, the said straight ties having forwardly and rearwardly extending tongues under the rails for attaching the rails to 80 the straight ties.

In testimony whereof, we have signed this specification in the presence of two subscribing witnesses.

WILLIAM HENRY MORGAN.
WALTER V. HARTZELL.
